UNITED STATES PATENT OFFICE.

OTTO WALTER, OF HANOVER, GERMANY.

VULCANIZER.

1,104,722.

Specification of Letters Patent.

Patented July 21, 1914.

Original application filed March 14, 1911, Serial No. 614,328. Divided and this application filed November 20, 1912. Serial No. 732,474.

To all whom it may concern:

Be it known that I, OTTO WALTER, a subject of the King of Prussia, and residing at Hanover, Germany, have invented certain new and useful Improvements in Vulcanizers, of which the following is a specification.

My invention relates to vulcanizers and is particularly designed for carrying out the process described in my Patent 1,052,430, dated Feb. 4, 1913, of which the present application is a division.

The new vulcanizing mold permits of placing in the heating chamber of the mold at the predetermined vulcanization spot a greater or less quantity of the pre-heated live coals which serve to produce the vulcanization. Beneath the coals supporting pins or a grate may be arranged in the vulcanizer, which according to the form of the body heated or the vulcanization spot may be specially shaped.

Instead of live coals, many other suitable sources of heat may be substituted to secure a local heating of the mold; for example a gas heated body, the form of which corresponds to the surface to be vulcanized. An electrically heated body, the heating source of which is preferably separately arranged, may also be employed.

In the accompanying drawings, Figure 1 is a side elevation partially in section of a device for vulcanizing tubes; Fig. 2 is a vertical cross section of the same; Fig. 3 is a plan view of the lower member of the heating chamber; Fig. 4 is a vertical section of a vulcanizer for repairing tires; Fig. 5 is a plan thereof, partially in section; and Fig. 6 is a side elevation of a modification of the heating means.

Referring to Figs. 1 to 3 the invention is here illustrated in a vulcanizer comprising a heating-chamber *a* with cover *b*, clamped to the base *e* of wood or other suitable material by slotted links *c* carrying screws *d* which bear upon the lugs *f* projecting through the slots in the links. The latter are rigidly connected to the base by the transverse pin *g*. Within the heating chamber *a* is arranged near the bottom a grate *h* on which is placed at the predetermined spot the heat generating live coal *i* which produces the vulcanization at the desired place. The heated air escapes through the chimney *k*, while fresh cool air enters the chamber through side

holes *l* and serves to prevent overheating. The rubber body that is being treated is clamped in the usual way between the base *e* and the bottom of the heating chamber and is thus heated by the coal *i* only at the point at which it is desired to effect vulcanization. The apparatus shown in Figs. 4 and 5 in like manner show a heating chamber *a*¹, a cover *b*¹ and a base *e*¹, the adjacent faces of the vulcanizer box and base being shaped to receive a beaded tire of common form, and being curved longitudinally to conform substantially to the curvature thereof. A mandrel *m* may be arranged between the heating chamber and base, which will serve to support the tire and prevent its collapse when the mold plate is pressed down. The grate *h*¹ or other supporting means, on which the coals are placed is offset at *n* in order to keep the coals as thick as possible at the spot to be vulcanized and thus accelerate the vulcanization process.

The invention can of course be applied to the vulcanization of various rubber bodies, in which case as in the embodiments described, the heating box and base have the juxtaposed faces shaped to the object heated and the grate within the mold box adapted to the shape thereof for the purpose specified.

In Fig. 6 a burner *o* is shown for heating the mold by gas instead of by charcoal. In this arrangement the face plate *p* is preferably removable so that plates of various shapes may be employed which are suitably shaped to the object to be heated. Electricity may also be employed as above mentioned to heat the mold.

By the use of the vulcanizing method above explained, that is, through the use of a source of heat (for example live coals) which possesses and is adapted to maintain a temperature sufficiently high to completely vulcanize the rubber, a distinct advantage is obtained since the process may be successfully completed without using any testing appliance whatever.

The vulcanization process is not only simple and expeditious but after the body to be heated has been once placed in position no further oversight or regulation is necessary to insure complete vulcanization.

I claim as my invention:

1. A vulcanizer apparatus comprising a heating chamber adapted to receive live

coals, and means within the chamber for supporting said coals adjacent but out of contact with the bottom of the chamber, in combination with a base between which and the bottom of said heating chamber the article to be treated may be placed and means for firmly securing said parts together.

2. A vulcanizer apparatus comprising a heating chamber adapted to receive live coals, and a grate within the chamber for supporting said coals adjacent but out of contact with the bottom of the chamber, in combination with a base between which and the bottom of said heating chamber the article to be treated may be placed and means for firmly securing said parts together.

3. A vulcanizer apparatus comprising a heating chamber adapted to receive live coals and having a bottom transversely curved to the shape of a tire, a stepped grate for supporting said coals adjacent but out of contact with the bottom of the chamber, in combination with a base between which and the bottom of said heating chamber the article to be treated may be placed and means for firmly securing said parts together.

4. A vulcanizer apparatus comprising a heating chamber adapted to receive live coals and having a bottom transversely curved to the shape of a tire and means within the chamber for supporting said coals adjacent but out of contact with the bottom of the chamber, in combination with a base between which and the bottom of said heating chamber the tire may be placed, a mandrel conforming substantially to the inner cross section of the tire and adapted to be placed therein during the operation of the vulcanizer, and means for securing together the heating chamber and base with mandrel and tire interposed.

5. A vulcanizer apparatus comprising a heating chamber adapted to receive live coals, a readily opened cover therefor with vent for gases arising from the coals, means within the chamber for supporting said coals adjacent but out of contact with the bottom of the chamber, in combination with a base between which and the bottom of said

heating chamber the article to be treated may be placed and means for firmly securing said parts together.

6. A vulcanizer apparatus comprising a heating chamber adapted to receive live coals, a readily opened cover therefor with vent for gases arising from the coals, means within the chamber for supporting said coals adjacent but out of contact with the bottom of the chamber, the walls of said chamber being perforated to permit the entry of air into said chamber, in combination with a base between which and the bottom of said heating chamber the article to be treated may be placed and means for firmly securing said parts together.

7. A vulcanizer apparatus comprising a heating chamber adapted to receive live coals, a readily opened cover therefor with vent for gases arising from the coals, means within the chamber for supporting said coals adjacent but out of contact with the bottom of the chamber, the walls of said chamber being perforated at a point below the coal-supporting means to permit the flow of air over said coals to the vent, in combination with a base between which and the bottom of said heating chamber the article to be treated may be placed and means for firmly securing said parts together.

8. A vulcanizer apparatus comprising a heating chamber having a bottom adapted to contact with the article treated, a grate within said chamber for supporting live coals adjacent but out of contact with said bottom at a predetermined point within the chamber at which vulcanization is desired, in combination with a base beneath the bottom of said chamber and means for clamping said chamber on said base to hold an interposed article in close contact with the bottom of the chamber.

In testimony whereof I have signed my name to this specification in the presence of two subscribing witnesses.

OTTO WALTER.
